UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

RANGE

Application filed May 23, 1931. Serial No. 539,566.

This invention relates to improvements in ranges, and it pertains particularly to an improved type of cover for the cooking top portion of the range.

5 The improvement specifically shown involves a cover for the cooking burners or top portion consisting of two separate portions that are individually hinged at opposite sides of the said top portion, whereby the outer portion when it is open serves as a working space and the inner portion when it is raised serves as a splasher back.

In the construction as here shown, this cooking top cover is made of two parts which 15 have their outer portions independently hinged to the cooking top portion, the inner part of the cover being hinged to or adjacent to the inner projecting wall of the oven portion, and the other part of the cover having 20 its outer side hinged at a point inside of the outer extremity of the said cooking top portion, whereby when the outer portion is opened outward it is held in a horizontal position and is adapted to act as a working 25 shelf or space, and the other part of the top when it is raised extends upward parallel with and adjacent to or against the adjacent outer wall of the oven portion and acts as a splasher back for the inner end of the cooking 30 top portion.

A further improvement is hinging the inner part of said folding top in a detachable manner whereby the said cover can be removed for cleaning purposes.

35 Other improvements pertain to certain details which will be described hereinafter.

In the accompanying drawings:

Figure 1 is a front elevation of a range embodying the present improvement, the 40 folding top portion being shown in closed position.

Fig. 2 is a front elevation of the range showing the folding top portion in open position.

45 Fig. 3 is an enlarged sectional view of the lower hinged end of the inner cover portion showing that it is detachably hinged to the cooking top portion.

Fig. 4 is an enlarged vertical sectional view 50 through the hinged portion of the outer mem-

ber of the folding top, the same being shown in section and also the frame of the cooking top portion shown in section.

Fig. 5 is a top plan view of a range with the present improvement applied to it and 55 showing the folding top portion in open position.

Fig. 6 is a top plan view of the range showing the folding top or cover in a closed position.

Fig. 7 is a view of a range showing a modification in a manner of supporting the outer cover member in its open position.

Fig. 8 is a front elevation of Fig. 7, with the folding top portion closed.

Fig. 9 is a front elevation showing a modification in the manner of hinging the inner folding top member, the folding top members shown partially open.

Fig. 10 is a top plan view of the range 70 shown in Fig. 9 and also showing the supporting member extending substantially across the end of the range, whereby it is adapted to receive either drawers for cooking utensils or made into other elongated utensil 75 holders.

Referring now to the drawings in which a baking oven 1 and below it a broiling oven 2 are suitably supported upon a frame 3. Also supported on this frame 3, at the inner side 80 of said oven portion is a compartment portion having preferably two doors 4, and above this compartment is located what may be either termed a burner box or a cooking top portion 5. Located on top of this burner 85 box is a suitable frame 6, and located in this frame is a grate member 7. This grate member is made detachable in the usual manner and in referring to the cooking top portion is meant that part which comprises the burner box 5. Located above the burner box and at its rear end is a vertically arranged splash- 90 er back 8, that is preferably fixed in said vertical position.

Attention is called to the fact that the compartment 4, the burner box 5 and the frame 6 are elongated upwardly so that the said frame 6 is located in a horizontal plane approximately half-way the height of said baking oven 1.

In carrying out the present invention, I provide said cooking top with a folding cover which comprises an inner member 9 that has its inner end hinged adjacent the vertical outer wall 10 of said oven, said hinge extending in a direction transverse the said cooking top and also consists of an outer member 11, which has its outer edge hinged at 12 to the cooking top portion. This hinge member 12 extends also in a direction across the cooking top portion.

When the folding top members 9 and 11 are in open position the inner member 9 has its upper edge in substantially a horizontal plane with the upper edge of the splasher back 8, and the member 11 is of the same width so that when these members 9 and 11 are in closed positions, their inner edges 13 are close together. By positioning the burner box to bring the grate portion at a point substantially mid-way between the top of the inner wall 10 and its bottom, the above positions of the parts are accomplished.

It will be also observed that the members 9 and 11 are independently hinged and move independently. The foregoing result is accomplished by positioning the burner box 5 to a point that is substantially half the distance of the horizontal length of the cooking top, and this makes the distance from the upper edge of the splasher back to the cooking top substantially one-half the horizontal length of the cooking top and accomplishes the horizontal and vertical positions and sizes of the folding members 9 and 11.

For the purpose of supporting the outer member 11 in its horizontal position in order that it will form a working shelf or space, the outer member is hinged at the point 12 that is located at a point inside of the outer edge 13 of the cooking top, whereby the number 11 is supported as stated.

I show in Fig. 4 the specific manner of constructing the parts so that the above result is accomplished. In this figure the cooking top frame consists of an upper metallic sheet or member 14 having turned down sides. This metallic member 14 is so shaped at its outer end that it forms an L-shaped depending portion 16, which is of a depth corresponding to the thickness of the said folding member 11. This folding member 11 also consists of an upper sheet-iron portion 17 and a lower sheet iron portion 18, the said upper and lower portions telescoping as shown at 19. The above construction may be varied without involving the broad idea. The improvement shown in Fig. 4 and Figs. 1, 2, 5 and 6, is forming in the outer edge of the top portion a depending L-shaped construction to receive and support the member 11 in its horizontal position for the purpose herein stated.

The specific manner of pivotally connecting the folding member 9 with the cooking top portion is shown in Fig. 3. This consists

in providing the cooking top 6 at each side with upwardly projecting sockets 20 and in providing the said member 9 at each side thereof the pintles 21, which rest in the sockets 20. These sockets 20, as clearly shown, have open upper ends adapted to detachably receive the said pintles 21. For the purpose of detachably holding these pintles 21 in the sockets 20 and for holding the said folding member 9 in a vertical position the pintles 21 are provided with slight projections 22 and providing a light spring member 23 adapted to engage these pintles and projections. The said member 9 consists of an outer lower sheet-metal wall 24 and an inner or upper wall 25, and that the lower ends of these walls interlock as shown at 26. These interlocking walls are provided with slots 27 adapted to receive the upwardly projecting sockets 20.

By means of the foregoing construction it will be seen that the member 9 and the pintles can be inwardly removed from the sockets 20 and replaced therein by an outward movement. By making these members detachable it enables the structure to be readily cleaned.

In Figures 7 to 10 inclusive, I show a modification in the manner of supporting the outer folding top 11' in its open position. This modification consists in Figs. 7 and 8, in providing a member 28 that extends laterally outward from the vertical wall 29 of the frame 3. The upper face of this member 28 is located in a horizontal plane which corresponds with the horizontal plane of the top portion of the folding member 11', when it is open to its horizontal position. In these figures the hinge 12' is of the same type as shown in Figs. 1 to 6, inclusive, but the frame or top member 6 of the burner box is not provided with the L-shaped portion shown in Fig. 4. As a consequence the member 11' extends to or substantially to the outer edge of the top member 6. In Figs. 7 and 8, the inner folding top member 9 will preferably be detachable in the same manner shown in Fig. 4. The supporting member 28 extends substantially horizontally throughout the width of the range. Therefore, this member 28, as shown, is provided with openings 30 and 31, that may be provided with drawers (not shown) to receive utensils or the members 28 may be formed otherwise to receive utensils.

In Fig. 9, I show a modification in the manner of hinging the member 9 to the top or frame 6. This consists in a suitable link 32 that has its outer end pivotally connected at 33 with the member 9, its inner end 34 suitably connected with the top member or frame 6.

The top member 6 may be constructed so that the link member 32 may enter it when the folding top member 9 is horizontal, or the wall 10 of the baking oven 1 may be con-

structed to permit the said member 32 to enter it, or the member 9 may have recesses or openings to accommodate the link member 32 when the said member is either open or closed, or the said member 9 may simply open against the link 32 and close against the link 32. The link member 32 is preferably detachably connected at its lower end with the top member 6.

10 While I have described in considerable detail the specific construction of the present improvement, I wish it to be understood that variations in constructions from that shown and described may be made without departing from the scope of the present invention so long as such changes are within a liberal interpretation of the appended claims.

15 Having thus described my invention, what I claim and desire to secure by Letters Patent is:

20 1. A range having a cooking top and a folding cover therefor consisting of an inner and an outer member extending transverse the cooking top, the inner member connected at its inner end to be movable to a vertical position and the outer member connected at its outer end with the cooking top at a point inside of the outer edge of said cooking top, whereby the latter member when moved to horizontal position is supported therein to form a working space.

25 2. A range having a cooking top provided with a cover consisting of an inner transversely extending member and an outer transversely extending member, the inner end of the inner member pivotally supported to be moved to a vertical position, the outer end of the outer member pivoted to the cooking top at a point inside of the outer edge of the cooking top and the cooking top cut out to permit the last mentioned movable member to assume a horizontal position and to be supported in said position.

30 3. A range having a cooking top, a two-part cover therefor, said cover consisting of inner and outer independently movable members, said outer member pivoted at its outer end to swing in a horizontal position, means for supporting the same in said horizontal position, and the inner member supported by the cooking top portion, open top socket members receiving laterally extending pintles on the inner portion of the inner member, for the purpose set forth.

35 4. A range comprising a cooking top and a two-part folding cover therefor, said cover consisting of two independently movable transversely arranged members, the outer member pivoted at its inner end to swing to a horizontal position, means for supporting said last mentioned member in its horizontal position, the inner member pivotally supported at its inner end with the inner side of said cooking top by means of upwardly projecting open top sockets receiving laterally

extending pintles carried by the inner member said pintles having projections, and springs connected with the cooking top engaging the said pintles and the said projections whereby the inner member is detachably held in its vertical position.

5. A range comprising a baking oven and a broiling oven and a cooking top portion located at one side thereof and below the top of the upper of said ovens, said cooking top portion having a two-part cover consisting of inner and outer transversely extending members, the said inner member pivotally connected at its inner end with the inner end of said cooking top portion and the outer member pivotally connected at its outer end with the outer end of said cooking top portion, a vertical splash back located at the rear edge of the cooking top portion having its upper edge in substantially a horizontal plane with the top of said upper oven, and said cooking top portion located below the said horizontal planes of the top of said upper oven and the upper edge of the splash back a distance equal to one-half of the horizontal length of the cooking top and said inner and outer cover members having a width corresponding to the distance from the cooking top to the upper edge of the splash back, whereby the parts fit in as described.

6. A range comprising an oven and an open burner portion located at one side of and below the upper end of the said oven, a cover for the open burner portion comprising an inner and an outer transversely arranged portion, said outer portion pivotally connected with the outer side of the said open burner portion, the inner member pivotally connected with the inner portion adjacent the junction of the said oven and the open burner portion, the outer member pivoted to the outer portion of said burner portion to be supported in a horizontal position, the parts arranged for the purpose specified.

7. A range comprising an upper and a lower oven, an open burner portion located in a horizontal plane below the top of said upper oven, a fixed vertical splash back located at the inner side of said open burner portion, the top of the splash back being substantially in a horizontal plane with the top of said upper oven, an inner and an outer cover for the said open burner portion the inner ends of both of said covers being free and the outer end of the outer cover portion pivoted to the outer end of said burner portion, the inner end of the inner cover portion pivoted to the inner end of the open burner portion and swinging in a vertical position parallel to and substantially against the adjacent upwardly extending part of said upper oven, said cover portions being of a width substantially equal to the height of the splash back portion, whereby said cover portions when in open positions form together with the top burner

portion an L-shape whereby the inner cover portion is out of the way of cooking utensils and is supported in said vertical position, the parts operating as described.

- 5 8. An improved range comprising an upper and a lower oven, an open burner portion located at one side and below the top of the upper burner portion, a vertical splasher back for the burner portion of a width substantially equal to the distance of the burner portion below the top of said upper oven, inner and outer cover portions for said burner portion, said cover portions being in width equal to the length of the burner portion and 10 15 equal in length to the height of the splasher back, said inner cover portion having its inner end pivoted to swing in a vertical position substantially against and parallel the adjacent side of the oven portion and the outer cover portion having its outer end pivoted with the burner portion to swing outwardly horizontally, said top burner portions 20 25 having their inner edges swinging free of the said splasher back, whereby said cover portions can be made to occupy the positions described.

In testimony whereof I hereunto affix my signature.

ARTHUR STOCKSTROM.
